HYMAN ROSEN
BY Morris Fischstein
ATTORNEY

UNITED STATES PATENT OFFICE.

HYMAN ROSEN, OF NEW YORK, N. Y.

BUTTON-MAKING MACHINE.

Application filed December 30, 1921. Serial No. 525,999.

To all whom it may concern:

Be it known that HYMAN ROSEN, declarant citizen of the United States, subject of the Government of Russia, residing at the city of New York, in the county of Bronx and State of New York, has invented certain new and useful Improvements in Button-Making Machines, of which the following is a specification.

10 This invention relates to button making machines, and is particularly directed to machines used in the manufacture of cloth covered sheet metal buttons.

15 One object of this invention is to provide a button making machine of the character described which shall be adapted for securing a stem to the button simultaneously with its formation so that several buttons so formed may be held together by 20 their stems to provide an ornamental cluster which may be used in trimming ladies' apparel such as a dress or millinery.

Another object thereof is to provide a button making machine of the character described which shall be adapted for making a continuous string of buttons held on a common stem, extending from the sides of the button.

30 A further object is to provide a button making machine for buttons of the character described which shall be adapted for providing the button simultaneously with the forming of the button with a stem or end whereby it may be attached to a garment 35 or secured to another button for the purpose of forming an ornamental decoration.

40 A still further object is to provide a machine of the character described which shall be simple in construction and efficient in operation to a high degree.

Other objects of this invention will in part be obvious and in part hereinafter pointed out.

45 The button herein shown and described is described and claimed in my co-pending application, Serial No. 577,209, filed in the United States Patent Office on the 24th day of July, 1922, and accordingly is not claimed herein.

50 With the above exception the invention accordingly consists in the features of construction, combinations of elements and arrangement of parts which will be exemplified in the construction hereinafter de-

scribed and of which the scope of application will be indicated in the following claims.

In the accompanying drawings, in which is shown one of various possible illustrative embodiments of this invention,

Fig. 1 is a side elevational view partly in section showing the position of the upper and lower formers of the machine in readiness for the first step of the operation,

Fig. 2 is a similar side elevational view partly in cross-section showing the lower and middle formers in position for the second step in the operation, and the upper former with one-half of the button therein resulting from the first step in the operation;

Fig. 3 is a side view partly in section showing the three formers in position for the third step in the operation and with a stem in place ready to be clamped in position simultaneously with the closing of the two shells of the button in operation;

Fig. 4 is a plan view of one type of intermediate former embodying the invention;

Fig. 5 is a cross-sectional elevation of a modified intermediate former;

Fig. 6 is a detail view showing in section a complete button with stem extending therefrom as manufactured by the machine embodying this invention;

Fig. 7 is a view showing an ornamental cluster made from buttons according to the present invention; and

Fig. 8 is a view showing a continuous string of buttons manufactured with the machine embodying this invention.

Fig. 9 shows the lower and intermediate former in the position shown in Fig. 2 but with the parts in the position they assume after the intermediate former has been pushed down so as to compress the spring 18; and

Fig. 10 shows the lower, intermediate and upper former in clinching position for completing the button.

Referring in detail to the drawing, the lower former comprises a base 10 having a stepped portion 11 from which upstands a plug 12. Slidably mounted on this plug is 105 a holder 13, the vertical movement of which is limited by a screw 12' extending into a slotted portion 14 of the plug, as will be

readily understood. The holder is recessed at the top to provide an annular shoulder 15 and is further interiorly recessed as at 16, the top wall of the latter recess being beveled as at 16^a. Held between the shoulder 17 of the holder and the base 11 is a helical compression spring 18.

The upper former comprises a holder 19 having a plunger or follower 20 operating in the central recess 21 of the holder. The lower end of the follower 20 is recessed as at 22 to conform to the configuration of the shell of the button. The vertical movement of the plunger 20 is similarly limited by a screw 23 which extends into a slotted portion 24 of the follower. Extending from the upper former is a latch member 25 pivoted to a collar 26 held on the plunger. The latch member is provided with a notch 27 whereinto enters the flange 28 of the holder 19, and is further provided with a cut-away cam face 29 whereby the latch may be tripped by the intermediate former as hereinafter described. The holder 19 has a lower flange 30 adapted to enter into the upper recess of the holder 13 and act against the shoulder 15 thereof.

The intermediate former comprises a clamping block 31 adapted to serve also as a holder, and is provided with a follower 32 operating in the recess 33 having a beveled top wall 33^a. This follower 32 has an enlarged end 32^a shaped to conform to the top of the plug 12. The opposite end 35 is provided with a cylindrical recess 34. The vertical movement of the follower 32 is similarly limited by a screw 35 extending into the slotted portion 36. The holder 31 has a beveled head 38 and is provided at 40 the bottom with a flange 37 adapted to enter into the top recess of the holder 13 to act against the shoulder 15 thereof. An annular shoulder 39 is depressed from the top face of the holder forming an annular recess 40 adapted to receive the lower flange 30 of the upper holder 19. Spaced grooves 41 are cut in the top of the holder 31 and these extend across the beveled head 38 and the annular shoulder 39 and the beveled wall 33^a of the recess 33, for the purpose hereinafter explained.

The operation of the machine is as follows: In the first step (see Fig. 1) a shell 42 is placed in the holder 13 of the lower former in the beveled recess 16 above the plug 12. A piece of cloth 43 of desired size and color is then placed on the annular shoulder 15. By operation of the foot press 44, the upper former is pressed down against the lower former so that the flange 30 of the holder 19 abuts against the annular shoulder 15 of the holder 13. The upper former causes the lower holder to be pushed down against the spring 18, thus forcing the cloth 43 over the shell 42. In

this operation by reason of the larger diameter of the cloth 43, the latter is slightly crimped over the edge of the shell 42 as shown at 44', the cloth covered shell entering into the recess 41 of the upper former 70 (see Fig. 2) which thus now holds one-half 45 of the cloth covered button in readiness to be united with the other half which is formed in the second operation. In this first operation, the follower 20 of the upper 75 former does not move relatively to the holder 19, the latch 25 locking the holder in position by means of the notch 27 and the annular flange 28 as already described.

In the second operation (see Fig. 2), a similar shell 46 and piece of cloth 47 are positioned in the same way in the lower holder 13. The intermediate former is then inverted in place over the lower former with the bevel head 38 of the intermediate 85 former entering the upper recess of the holder 13 just above the annular shoulder 15. The intermediate former is then pressed down against the lower former, the holder 13 moving down compressing the spring 18 90 as in the first operation. As a result of this operation, another shell 46 is covered by the cloth 47 the latter being likewise slightly crimped over the edge of the shell 46 as at 48 and the complete covered shell 95 is transferred to the recess 33 of the intermediate former.

In the third step of the operation (see Fig. 3) the intermediate former is removed from the lower former and turned upright 100 into its normal position with the other half of the button 49 disposed in opposed relation to the first half 45 in the upper former. The two halves 45 and 49 are now ready to be closed on each other to complete the 105 button. This is done by pressing the upper former down against the intermediate former which now rests with its lower flange 37 on the shoulder 15 of the holder 13, and the enlarged head 32^a over the top 110 of the plug 12. Before pressing the parts together, however, a piece of thread or wire 50, or other material suitable to form the stem of the button is placed in one of the grooves 41 and extends beyond the groove 115 for a short distance as at 51 over the lower half 49 of the button. The upper former is then pressed against the intermediate former, the cam face 29 of the latch 25 riding along the bevel head 38 of the upper 120 former, thus unlocking the latch from the holder 19, the lower flange 30 of which enters into the recess 40 and acts against the annular shoulder 39. As a result of this operation, the upper half 45 is closed about 125 the lower half 49 with the stem 50 held between the two and extending from the side of the button as clearly shown in Fig. 6.

In the modified form shown in Fig. 5, the intermediate former instead of having 130

grooves cut in the head thereof is pierced at the sides as shown at 52 to receive the stem pieces 50.

It will be understood of course that any number of spaced grooves may be provided and when desired more than one stem may be crimped into the button in the third operation. Thus, in Fig. 4, four grooves are shown and if prior to the pressing operation of the third step a stem is inserted in each of said grooves, the resulting button will have extending symmetrically from the side thereof four stems. The free ends of each of these stems may be used in connection with other buttons thus forming a symmetrical ornamental group. It will also be clear that a continuous string of buttons such as shown in Fig. 8 may be produced merely by drawing the button and stem across the head of the intermediate former and continuing to close two shells about any desired length of wire or thread 50 at any desired intervals. Again, if desired, a plurality of single buttons with stems, such as result from the third operation may be grouped together in cluster formation as shown in Fig. 7 by intertwining their stems, thus providing an ornament suitable for millinery purposes or for other forms of decoration.

Briefly described, among the dominant features of this invention is the provision in a machine for making cloth covered sheet metal buttons of means whereby a stem may be secured to the button in a manner so as to extend from the side thereof simultaneously with the closing of the parts of the button. The particular position of the stem so as to extend from the side of the button, it will be understood, is what makes possible the attaching or grouping together of several buttons in ornamental formation and also the provision of a continuous string such as shown in Fig. 8. Especially when the material used for the stem is wire, it is possible to produce a varied number of ornamental formations by merely taking a given length and twisting or coiling it to produce the desired ornamental group. It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a button making machine, in combination with means for forming the parts of the button, means for assembling said parts to complete the button, said latter means adapted to position a stem to be so secured to said button as to extend from the periphery of the button.

2. In a button making machine, in combination with means for forming the parts of the button, means for assembling said parts to complete the button, said latter means adapted to position a stem so as to be secured simultaneously with the completion of the button to extend from the periphery thereof.

3. In a button making machine, a pair of dies for assembling button parts, one of said dies having a central recess and an opening extending from the periphery of the other die to the walls of said recess adapted to receive a button stem.

4. In a button making machine, a die comprising a male and female member, the latter being provided with slots extending to the outer periphery of the female member adapted to receive a stem which extends from the periphery of the button.

5. In a button making machine, a die comprising a male and female member, the latter being provided with radial slots extending from the inner to the outer periphery of the female member adapted to receive a stem which extends from the periphery of the button.

6. In a button making machine, a pair of dies for assembling button parts, one of said dies having radial grooves to position a stem to extend peripherally from the button, the approach of said dies being limited to prevent the intersection or closing of the grooves by the opposing die parts.

In testimony whereof I affix my signature.

HYMAN ROSEN.
